UNITED STATES PATENT OFFICE

LEO J. PALDA, JR., OF MINOT, NORTH DAKOTA

TUYÈRE AND SUPPORTING GRATE THEREFOR

Application filed February 8, 1929. Serial No. 333,473.

The present invention relates to a tuyère and supporting grate therefor and the object and advantages of the invention will become apparent as the description proceeds when considered in connection with the accompanying drawings, wherein:

Figure 1 is a vertical section through the tuyère and the supporting grate associated therewith,
 10 Figure 2 is a top plan view of the tuyère,
 Figure 3 is a top plan view of the top grate ring disk,

Figure 4 is an edge elevation thereof,

Figure 5 is a detail view of the edge showing the shaker bar recess,

Figure 6 is a top plan view of the bottom or lower grate ring disk, and

Figure 7 is a side elevation thereof.

Referring to the drawing it will be seen 20 the tuyère is in the form of a casting and includes a frusto-conical body 5 merging into a cylindrical skirt the exterior diameter of which is less than the lower end of the body 5 so as to form an annular shoulder 7. The 25 upper end of the body 5 merges into a downwardly and inwardly extending conduit 8 curving outwardly through the skirt forming a socket 9 to receive coal pipes.

An air inlet 10 is provided in the side of 30 the skirt adjacent the socket 9. The body 5 is provided with a plurality of horizontal openings as indicated at 12, said openings being of arcuate formation and arranged in coaxial series.

35 A lower ring disk like grate 15 rests on flanges 16 being anchored in place as at 17. Radial slots 18 are formed in this lower grate 15. The lower grate is formed in two sections having interlocking connections 19.

40 The numeral 20 denotes an upper ring disk like grate resting on the grate 15 and disposed about the lower end of the body 5, it being noted that the shoulder 7 rests on the inner portion of the grate 15. This grate 20 45 is formed with radial slots 21 which may be placed into or out of registry with slots 18.

Interlocking connections 22 are provided between the sections of the grate 20. A portion of the grate 20 is provided with a shaker 50 receiving recess 24.

From the above detailed description it will be seen that I have devised a tuyère and grate for furnaces which is simple in its construction, inexpensive to manufacture, easy to manipulate, thoroughly efficient and reliable in use and otherwise well adapted to the purpose for which it is designed.

Particular attention is directed to the air chamber formed in the casting and the horizontal passages through the air vents or openings 12 so that no ashes or fuel can drop into the chamber.

With the use of this tuyère air is not blown through the ash box or ash receptacle but comes in with no possibility of blowing ashes or dust out of the furnace or steam plant. The grate arrangement of the two plates one above the other is important in that the upper is movable so as to make a natural air draft or to drop the ashes.

The arrangement is such that slack or dust can be burned without dropping the unburned fuel and may be used in connection with the tuyère which I have described.

It is thought that the construction, utility and advantages of this invention will now be quite apparent to those skilled in this art without a more detail description. The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A tuyère and supporting grate therefor of the character described comprising a fixed, sectional, flat grate disk having a central opening, a shiftable, sectional grate disk mounted co-axially on the fixed grate disk in superposed relation thereto and having a centrally disposed opening of greater diameter than the opening in said fixed disk, and a

tuyère removably disposed in the opening in the flat disk comprising a substantially frusto-conical portion, a depending skirt portion of less diameter than the adjacent end of the frusto-conical portion providing an annular shoulder for engagement on the fixed disk for supporting the tuyère thereon, the shiftable disk encircling the lower end portion of the frusto-conical portion of the tuyère and adapted to rotate therearound.

In testimony whereof I affix my signature.

LEO J. PALDA, JR.
